UNITED STATES PATENT OFFICE

ADOLPH T. HAMBERGER, OF SCOTLAND, SOUTH DAKOTA

AUTOMATIC SPEED-GOVERNING DEVICE FOR INTERNAL-COMBUSTION ENGINES

Application filed April 17, 1928. Serial No. 270,711.

The present invention relates to improvements in speed responsive devices and has reference more particularly to a governor for automatically actuating the throttle valve for 5 association with an internal combustion engine when a predetermined speed is attained.

One of the important objects of the present invention is to provide an automatic speed governing device which is adapted for 10 association with an internal combustion engine that is used as a stationary engine, and wherein the motor is employed as a source of external power such as for instance in driving a saw or other machinery.

15 A further object is to provide a device of the above mentioned character wherein the same can be readily and easily attached on an internal combustion engine without necessitating any material alterations of the parts 20 of the engine with which said automatic speed governing device is associated.

Still a further object is to provide an automatic speed governing device for internal combustion engines of the above mentioned 25 character which will at all times be positive and efficient in its operation, the same being further simple in construction, inexpensive, strong and durable, and further well adapted to the purpose for which it is designed.

30 Other objects and advantages of the invention will become apparent from the following description when taken in connection with the accompanying drawings.

In the accompanying drawings wherein 35 like reference characters indicate corresponding parts throughout the several views thereof:

Figure 1 is a side elevation of the automatic speed governing device embodying my invention 40 showing the same mounted on an internal combustion engine.

Figure 2 is a sectional view taken approximately on the line 2-2 of Figure 1 showing the centrifugal governor that forms a part 45 of the present invention.

Figure 3 is a horizontal section taken approximately on the line 3-3 of Figure 1 looking downwardly, and

50 Figure 4 is a detail perspective view of the sleeve that is slidable on the driven shaft for

cooperation with the slidable collar of the governor, showing the arm depending therefrom.

In the drawings wherein for the purpose of illustration is shown the preferred embodiment of my invention, the numeral 1 designates generally an angular bracket of substantially L-shaped configuration, the horizontal arm thereof which is denoted by the numeral 2 being secured at its free end 55 to the side of the block of the internal combustion engine A as at 3, the vertical arm 4 of this L-shaped bracket 1 is formed at its lower end with an attaching foot 5 that is secured to the supporting base 6 provided 60 for the internal combustion engine A when the same is employed as a stationary engine for utilizing the motor as a source of external power to drive a saw or other machinery.

An arm extends outwardly from the bend 70 of the L-shaped bracket 1 and is attached to the fan shaft supporting bracket 8, the fan shaft being shown at 9 in the dotted lines, while the pulley secured on this shaft 75 is shown in full lines at 10. The fan belt 11 which drives the fan pulley 10 and the shaft 9 is of a conventional construction. A bearing 12 is arranged on the outer side of the vertical arm 4 of the L-shaped bracket 1 80 as clearly indicated in Figure 1.

An additional bracket 13 is provided for association with the present invention, and this bracket 13 is secured at its upper end as at 14, while the lower end thereof extends downwardly adjacent the intake manifold 15 and is connected to the bolt 17 that extends through adjacent flanges of the intake manifold 15 and the carburetor 18 as also clearly shown in Figure 1. A bearing 19 90 is arranged on the intermediate portion of this bracket 13 for alignment with the bearing 12 for supporting the horizontally extending driven shaft 20.

This shaft carries on its forward end a 95 pulley 21 that engages with the fan belt 11 whereby said shaft 20 will be driven simultaneously with the rotation of the fan belt and the fan shaft 9. Associated with the rotatable driven shaft 20 is a centrifugal 100

governor which includes the spaced collars 22 and 23 respectively. The collar 22 is fixedly secured on the forward end portion of the shaft 20 while the other collar is adapted for slidable and rotatable movement on the shaft 20 rearwardly of the fixed collar 22. A pair of flat resilient metallic strips 24 and 25 are disposed on opposite sides of the shaft 20 and are secured to the respective collars in any appropriate manner.

Opposed weighted blocks 26 and 27 are carried by the intermediate portions of the springs 24 and 25, respectively, and as is clearly shown in Figure 2, each block is formed with a laterally extending lip 28 on one side thereof. A screw 29 is threaded through each lip and is formed at its inner end with an eye for receiving one end of a coil spring 30, the other end of the coil spring being secured to the adjacent side of the opposite weighted block.

A nut 31 is threaded on the respective screw for engagement with the outer face of the lip 28.

The slidable collar 23 is formed adjacent its rear end with an annular channel 32 in the outer face thereof, as is shown more clearly in Figure 1 for receiving the inner opposed ends of the hooked shaped lugs 33 formed on the forward end of a sleeve 34 at diametrically opposite points, as more clearly shown in Figure 4, and this sleeve is slidable on the rear portion of the shaft 20 with the collar 23. An arm 35 depends from the rear end of this sleeve and the lower extremity of the depending arm is slightly offset as shown at 36, for a purpose to be presently described.

40 A substantially horseshoe shaped bracket 37 encircles the lower smaller end portion of the intake manifold 15, the free ends of the bracket being bent downwardly for attachment to the bolts that connect the adjacent flanges of the intake manifold and the carburetor together. A stop forming pin 38 projects upwardly from the innermost arm of the horseshoe shaped bracket as shown in Figure 3, and also in Figure 1 for a purpose also to be presently described.

45 The throttle valve of the carburetor is shown in the dotted lines at 39 in the drawings, and the stem on which the throttle valve is arranged is shown at 40.

50 An arm 41 is secured on the upper end of the stem 40 for disposition above the top of the carburetor 18 and operatively connected to the outer end of the arm is one end of an L-shaped link 42.

55 A substantially U-shaped lever which is in the form of a flat bar and which is designated by the numeral 43 is pivotally secured at 44 on the upper face of the horseshoe shaped bracket 37, the pivoted end of the outermost arm being formed with a lateral extension 45

that is provided at its outer end with an opening 46 for receiving the free end of the offset portion 36 of the depending arm 35. The innermost portion of this U-shaped lever is slightly raised and the other arm is operatively connected to the adjacent end of the link 42 in the manner as clearly shown in Figure 3.

The operation of my improved automatic speed governing device may be readily obvious from the construction shown and described, and it will be apparent that when a predetermined speed is reached, the collar 23 will move inwardly toward the stationary collar 22 and the flat spring strips will be bowed outwardly and simultaneously with the forward sliding movement of the collar 23 on the shaft 20, the sleeve 34 will move forwardly on the shaft causing the offset lower end 36 to effect the forward swinging movement of the U-shaped lever 43 on its pivot 44 and by reason of the L-shaped link connection 42 between the U-shaped lever and the arm 41 that is associated with the stem 40, the throttle valve 39 will be actuated to regulate the flow of the fuel from the carburetor to the intake of the combustion engine through the intake manifold 15 and when the speed is reduced, the parts will again assume their normal positions. The pin 38 is positioned to be engaged by the arm 41 in a manner to arrest the opening movement of the throttle valve 39 when said valve reaches its wide open position, as illustrated in Figure 3 of the drawings.

It will thus be seen from the foregoing description, that I have provided an automatic speed governing device for association with internal combustion engines that are particularly adapted to be used as stationary engines for utilizing the motor as a source of external power to drive various machinery, and due to its simplicity, the governing device can be readily and easily attached on the engine without necessitating any material alterations of the parts of the engine with which said device is to be associated.

While I have shown the preferred embodiment of my invention it is to be understood that minor changes in the size, shape and arrangement of parts may be resorted to without departing from the spirit of the invention and the scope of the appended claims.

Having thus described the invention, what I claim as new and desire to secure by Letters Patent is:—

1. An automatic speed governing device for internal combustion engines comprising in combination, an engine provided with a throttle valve carrying stem, a substantially horse shoe shaped bracket encircling the lower portion of the intake manifold of the engine, and being secured in a stationary manner, a substantially U-shaped lever

pivoted at one end on the bracket and extending around the adjacent portion of the intake manifold, an arm extending laterally from the upper end of the throttle valve carrying stem, an L-shaped link operatively connecting the other end of the U-shaped lever with the outer end of said arm, and a lateral extension formed on the pivoted end of the U-shaped lever for attachment to a speed responsive device.

2. An automatic speed governing device for internal combustion engines comprising in combination, an engine provided with a throttle valve carrying stem, a substantially horse shoe shaped bracket encircling the lower portion of the intake manifold of the engine, the free ends of the arms of the bracket being directed downwardly to provide attaching lugs for the bracket, a substantially U-shaped lever pivoted at one of its ends on the inner end portion of one arm of the horse shoe shaped bracket, said lever extending around the adjacent portion of the intake manifold, an arm extending laterally from the upper end of the throttle valve carrying stem, an L-shaped link operatively connecting the other end of the U-shaped lever with the outer end of said arm, a lateral extension formed on the pivoted end of the U-shaped lever for attachment to a speed responsive device, and a stop forming pin struck up from the horse shoe shaped bracket for limiting the swinging movement of the arm that extends laterally from the upper end of the throttle valve carrying stem.

In testimony whereof I affix my signature.
ADOLPH T. HAMBERGER.
